UNITED STATES PATENT OFFICE.

CHARLES A. BREWER, OF CHICAGO, ILLINOIS, ASSIGNOR TO CHARLES A. BREWER & SONS, OF CHICAGO, ILLINOIS, A PARTNERSHIP CONSISTING OF CHARLES A. BREWER, NELSON C. BREWER, KENNETH E. BREWER, AND EVERETT R. BREWER.

SALES-BOARD.

1,309,350.

Specification of Letters Patent.

Patented July 8, 1919.

Application filed March 15, 1919. Serial No. 282,836.

To all whom it may concern:

Be it known that I, CHARLES A. BREWER, a citizen of the United States, residing at Chicago, in the county of Cook and State 5 of Illinois, have invented certain new and useful Improvements in Sales-Boards, of which the following is a specification.

This invention relates to what are commonly known as sales boards, of the character typically disclosed in Letters Patent to Brewer and Scannell No. 780,086, dated January 17, 1905. These devices consist substantially of a board containing a number of transverse holes in which are loaded 10 slips of paper containing various indicia, the ends of the holes being sealed by paper sheets, and the slips being ejected by a punch. These devices may be variously used, either for the vending and advertising 15 purposes set forth in the aforesaid Letters Patent, or as a game board for educational and amusement purposes; as, for instance, the paper slips may contain the letters of the alphabet printed thereon, and the 20 object of the game may be to see which of the players can first punch out enough letters to build a word, or the slip may contain numerals printed thereon and the object 25 of the game may be to see who can punch out the highest aggregate or sum in a given 30 number of punches.

These boards have heretofore to a considerable extent been provided with a hinged rear brace to support them in an inclined position, somewhat after the fashion 35 of an easel, as typically shown in the aforesaid patent; but the provision of such a rear brace interferes with the compact packing of these articles for storage and shipping 40 in quantities, necessitating considerably more packing space than is required for the plain rectangular boards when not equipped with the back brace. Hence, these articles are now largely put out with the 45 back brace or support omitted. This latter form of the device has one serious objection, arising out of the fact that many careless users thereof, in punching the slips out of the board, will lay the latter flat on 50 a table or counter and punch through from the top of the board. Of course, when thus manipulated no clearance is provided for the extrusion of the slip, and it is simply mashed down at the back of the board,

necessitating the picking up of the latter 55 and the reapplication of the punch to get the slip out.

The object of the present invention is to provide a simple and inexpensive means by which the board may be firmly supported 60 when in use at a safe distance above the surface of the table or counter to afford clearance for the discharge of the slips when the board is resting on such table or counter, and at the same time avoid the waste of 65 storage or shipping space when the boards are packed in quantities.

With this object in view, I have devised the improvement forming the subject matter of the present invention, which I will 70 now proceed to describe.

The invention is illustrated as to structure and mode of use in the accompanying drawing, in which—

Figure 1 is a rear elevation of the sales 75 board, broken out between its upper and lower ends, and showing the four removable legs of the board packed in the pocket provided therefor in the upper portion of the rear side of the board, together with a 80 frangible seal for holding them confined in said pocket;

Fig. 2 is a section on the offset line 2—2 of Fig. 1; and

Fig. 3 is a vertical section through the 85 lower portion of the board illustrating the manner of punching out the folded slips.

Referring to the drawing, 5 designates as an entirety the board itself which, in the instance shown, is made up of a plurality 90 of heavy cardboard sheets 6 pasted to produce a laminated structure and containing the transverse perforations or apertures 7. Both ends of these apertures are sealed by thin sheets 8 of easily perforated paper, and 95 over the sheets 8 are pasted thin perforated cardboard sheets 9 having holes registering with the main holes 7 and serving as guides for the application of the punch or key 10; the thin sealing sheets 8 being preferably of 100 a different, contrasting color from the outer guide sheets 9, so as to readily indicate the proper points of application of the key. Within the holes 7 are loaded the folded or curled paper slips 11 containing the 105 printed indicia or symbols, the character of which depends upon the use and purpose of the device.

In the four corners of the board, on the rear side thereof, I form round holes or sockets 12, in which are inserted removable pins or pegs 13 that constitute legs supporting the board on the table, indicated by the line 14 in Fig. 2. In the rear surface of the board, preferably above the series of perforations 7, I form a shallow recess or pocket 15 of a size just sufficient to compactly contain the four pins or pegs 13 within the surface boundaries of the board, as clearly shown in Fig. 1. When the board is prepared for shipment these pins or pegs, with their ends preferably coated with a dried adhesive, are set into the pocket 15, and a frangible seal, such as a slip of paper 16 is pasted over the open side of the pocket to retain the pins or pegs within the latter and prevent their accidental loss. When the board reaches its place of use, the seal is broken, the pins or pegs removed, their ends moistened and inserted in the holes 12, and the device then rests on the table or counter in the manner shown in Fig. 2, the board being firmly supported at a safe height above the surface of the table or counter to enable the slips to be forced out of the board by the punch 10 in the manner indicated in Fig. 3 without mashing the slips, as has heretofore been done with the board lying flat on the table or counter.

It will be readily seen from the foregoing how my present improvement accomplishes the stated objects of the invention. With the pegs 13 removed from the holes and packed and sealed within the pocket 15, the complete device occupies, for purposes of storage or shipment, only the space required by the board itself; and when the board has reached its place of use, it may be set up by merely breaking the seal, removing the pegs from the pockets and inserting them in the corner holes of the board. The legs are less expensive than a hinged back-brace, and they support the board more firmly while being punched. The blank space at the head of the board, both front and rear, is frequently used for advertising purposes, and it will be seen that my improvement does not appreciably interfere with the use of this space for such purposes.

Although I have shown and described a laminated board, it will be understood that this specific structure of board is not of the essence of the invention, since a one piece board of wood or other material may be

used, with the pocket to receive the legs of the board suitably mortised therein.

I claim:

1. A sales board of the character described, comprising a flat board having a perforated portion and an imperforate portion, said board further having holes in its rear side in the vicinity of the corners thereof and a pocket in one side of its imperforate portion, and supporting legs for said board adapted in the working position of the latter to be entered in said holes and in the idle position of said board to be stored in said pocket. 60

2. A sales board of the character described, comprising a flat board having a perforated portion and an imperforate portion, said board further having round holes at its corners extending part way therethrough from its under side and a shallow pocket in the under side of its imperforate portion, and supporting legs for said board in the form of round pins adapted in the working position of said board to tightly 75 fit said holes and in the idle position of said board to be stored in said pocket. 80

3. A sales board of the character described, comprising a flat board having a lower perforated portion and an upper imperforate portion, said board also having holes at its corners extending part way therethrough from its under side and a shallow pocket in the under side of its imperforate portion, supporting legs for said 90 board adapted in the working position of the latter to tightly fit said holes and in the idle position of said board to be stored in said pocket, and frangible means for retaining said legs in said pocket. 95

4. A sales board of the character described, comprising a flat board having a lower perforated portion and an upper imperforate portion, said board also having round holes at its corners extending part way therethrough from its under side and a shallow pocket in the under side of its imperforate portion, supporting legs for said board in the form of round pins adapted in the working position of said board to tightly fit said holes and in the idle position of said board to fill said pocket, and a seal pasted over the open side of said pocket completely closing the latter and confining said legs in said pocket. 100 105

CHARLES A. BREWER.
